UNITED STATES PATENT OFFICE.

HANS SCHWEITER, OF HORGEN, NEAR ZURICH, SWITZERLAND.

APPARATUS FOR CLEANING TEXTILE THREADS.

Application filed April 14, 1924, Serial No. 706,594, and in Switzerland April 25, 1923.

My invention relates to improvements in apparatus for cleaning textile threads, and more particularly in apparatus of the type in which the thread is pulled through an aperture made in a plate so that the impurities are removed by the edges of the aperture. I have found that by apparatus of this class such as are now in use and in which the aperture is in the form of a slot the threads are not sufficiently cleaned. The object of the improvements is to provide an apparatus by means of which the impurities are thoroughly removed, and with this object in view my invention consists in providing the cleaning apparatus with a polygonal aperture so that the thread is engaged by more than two edges, the aperture being preferably provided by two members one containing a radial notch and the other one a smooth face closing the notch to form the polygonal aperture.

For the purpose of explaining the invention an example embodying the same has been shown in the accompanying drawing in which the same reference characters have been used in all the views to indicate corresponding parts. In said drawing:

Fig. 1 is a section taken on the line A—B of Fig. 2,

Fig. 2 is a section taken on the line C—D of Fig. 1,

Fig. 3 is a top plan view,

Fig. 4 is an elevation of a part of the apparatus,

Fig. 5 is a partial elevation looking from the left in Fig. 4, and

Fig. 6 is an elevation of the notched member.

The apparatus is disposed on an angular bracket α made integral with a slotted ear α^1 for securing the same to a twisting machine. The bracket is in the form of an open ring α^2 having a sleeve c clamped therein by means of a screw b , and in the sleeve an axial pin d is shiftable. On the sleeve a drum e is rotatable which is locked as against axial displacement by an annular spring g engaging in a groove f of the sleeve c and in a groove h of the drum. At its end faces the drum is formed with triangular notches i , the depth of successive notches increasing in increments of about .1 millimeter, figures provided at the side of each notch indicating the depths of the notches in tenths of a millimeter. On a reduced portion d^1 of the pin d a drum k is loosely

mounted which shows a flange l located at the side of the drum e . The annular end face of the said flange is ground smooth and makes contact with the drum e so as to close the notches i to provide therewith triangular apertures. Furthermore by means of the nut m a casing n of porcelain is secured to the pin d which partly covers the drums e and k and is equipped at its upper extremity with a hollow thread guide p and at its side with an ear o . The casing has two opposite shoulders α and α^1 corresponding to the positions of the apertures for leading the threads into or out of the drum. To prevent accidental rotation of the drum e a nose q is formed on the bracket α engaging in any one of notches r provided at opposite sides of the drum e . The casing n is locked as against rotation by means of a pin s secured to the bracket α and engaging in the bore of the thread guide.

The thread s^1 to be cleaned is passed over the thread guide and passed through one of the notches i and a notch r and between the drums e and k , the attendant selecting the notch which corresponds to the diameter of the thread so that the thread makes contact with the angular faces of the notch and the drum k . For thus inserting the thread the attendant presses on a button u secured to the pin d which is thereby shifted inwardly against the tension of a spring t together with the drum k and the casing n . Now the thread is passed over the thread guide p and the ear o and below the apparatus it is slightly pulled to the right and rearwardly, so that it engages between the said drums and on the shoulders α and α^1 of the casing n , whereupon it is automatically shifted by the spring into the aforesaid path after releasing the button u . The ear o is made use of only when inserting the thread. When thus inserting the thread a large part of its circumference is engaged by edges for stripping off the impurities which are therefore entirely removed.

The cleaning apparatus described herein can be used for threads of different thicknesses, the notches i corresponding each to a specific thickness of the threads. The drum e is provided at both faces with a suitable number of notches i of different size and an equal number of notches r which are equal in size. Before inserting the thread to be cleaned the drum e is turned so that the notch i of the proper dimension is in

the upper position and exactly below the shoulder α and above the shoulder α^1 , so that the thread passes through the apertures without being bent. For locking the drum 5 in set position one of the notches r provided at the opposite side of the drum e is engaged by the lug q .

Should the notches i provided in one end face of the drum e be worn the drum e is 10 turned around so as to bring the notches of the opposite face into operative position.

To permit dismounting of the apparatus without any tools the drum e is pressed against the drum k by a spring t . The 15 spring t bears on the button u bearing on an enlarged portion v of the pin d . The button u shows a radial slot w broad enough to permit the reduced portion d^2 of the pin d to pass therethrough when pushing the button u inwardly and removing the same in 20 lateral direction. After thus dismounting the button the spring t is removed to the left in Fig. 1 and the pin d to the right.

While in describing the invention reference 25 has been made to a particular example embodying the same I wish it to be understood that my invention is not limited to the construction shown in the drawing, and that various changes may be made in the general 30 arrangement of the apparatus and the construction of its parts without departing from the invention.

For example I do not limit myself to a construction in which the notches r are provided in a pair of drums.

I claim:—

1. An apparatus for cleaning threads, comprising a pair of coaxially mounted laterally contacting circular members forming 40 an aperture of polygonal form between the same, and a spring pressing said members together, said members being relatively displaceable against the action of said spring.

2. An apparatus for cleaning threads, 45 comprising a support, a rotatable drum and

an abutting member mounted on said support coaxially and with adjacent end faces in contact with each other, said drum being formed at both sides with angular notches of different depths and with notches between 50 neighboring angular notches, and the abutting member having a plane face adjacent to the drum, said support having a lug in position for locking engagement with any one of the notches of the drum intermediate the 55 angular notches.

3. An apparatus for cleaning threads, comprising a support, a spindle mounted on said support, a rotatable drum and an abutting member both mounted on said spindle 60 with adjacent end faces in contact with each other, said drum being formed at both sides with angular notches of different depths and with notches between neighboring angular notches, and the abutting member having a 65 plane face adjacent to the drum, said support having a lug in position for locking engagement with any one of the notches of the drum intermediate the angular notches.

4. An apparatus for cleaning threads, 70 comprising a support, a spindle removably mounted on said support, a rotatable drum and an abutting member both mounted on said spindle with adjacent end faces in contact with each other, said drum being 75 formed at both sides with angular notches of different depths and with notches between neighboring angular notches, and the abutting member having a plane face adjacent to the drum, said support having a lug in 80 position for locking engagement with any one of the notches of the drum intermediate the angular notches, and a casing fixed on said spindle and enclosing said drum and annular member and having shoulders for 85 guiding the thread.

The foregoing specification signed at Zurich, Switzerland this 25 day of March, 1924.

HANS SCHWEITER.
